UNITED STATES PATENT OFFICE.

WILLIAM H. AVERILL, OF BOSTON, MASSACHUSETTS.

LOOSE-LEAF BINDER.

1,275,198.

Specification of Letters Patent. Patented Aug. 13, 1918.

Application filed October 25, 1916. Serial No. 127,592.

To all whom it may concern:

Be it known that I, WILLIAM H. AVERILL, a citizen of the United States, residing at Boston, in the county of Suffolk and State 5 of Massachusetts, have invented new and useful Improvements in Loose-Leaf Binders, of which the following is a specification.

The present invention relates to covers or binders adapted to hold a number of loose 10 removable leaves and is of a type which may be adjusted to various widths in order to hold a greater or smaller mass of leaves. More particularly the binder here shown as embodying the present invention is of the 15 same general nature as that disclosed in my prior application for Patent No. 66,920 filed December 15, 1915, patented December 19, 1916, No. 1,208,724 which embodies two cover members and telescopic hollow post elements 20 projecting from the respective members and equipped with locking means for locking the cover members at any desired distance apart within limits. The object of the present invention is to provide an improved means for 25 controlling and releasing the locks of the binder constructed and operable to control all of the locks in unison, to the end that the manipulation of a single control member may lock or release all of the locks, whereby 30 the separation of the cover members to permit insertion or removal of leaves is made simpler, and whereby also it is possible to provide a greater number of posts and locks than is possible where each of the locks requires individual manipulation.

The nature and principles of the means by which the foregoing and other objects are secured, and the special utility thereof are set forth in the following specification in 40 connection with the drawings and detailed description of one embodiment of the invention. In the drawings,

Figure 1 is a perspective view of a loose leaf binder embodying the present invention 45 with a collection of leaves associated therewith.

Fig. 2 is a sectional view on the line 2—2 of Fig. 1 showing in detail the locks and the controller therefor.

Fig. 3 is a plan view of that portion of the binder in which the locks and controller are contained.

Figs. 4 and 5 are sectional views on a larger scale of one of the locks and the controller therefor in locking and releasing 55 positions, respectively.

Fig. 6 is a perspective view of one of the latches which forms an element of the locking means.

The same reference characters indicate the 60 same parts in all the figures.

As in the prior application above specified the binder comprises two angular plates or jaws 11 and 12 to which are hinged cover parts 13 and 14, respectively, said jaws being so arranged that the flange 11^a of one overlaps the flange 12^a of the other. To the jaw 12 are connected hollow posts 15, 16 and to the jaw 11 are connected similar hollow posts 17, 18 of sufficiently smaller dimensions to enter and slide within the posts 15, 16, respectively. Conveniently the jaws and hollow posts are made of plate or strip metal, preferably steel, although I do not limit myself to any specific materials. Preferably also the hollow posts are formed by rolling flat blanks of the material into tubular form and abutting their opposite edges together. Preferably also the means for attaching the posts to the jaw members 11 and 12 respectively comprise tongues or tabs 19 on the ends of the posts 15 and 16, which are passed through slots in the jaw 12 and bent over on the outer side of such jaw; and similar tongues or tabs 20 (Figs. 3 and 4) 85 on the posts 17 and 18 which are passed through slots in the jaw 11 and bent over on the outer side of such jaw.

While the details of construction, manufacture, and assembly, above described are 90 preferable from the standpoint of economy, they are not essential to the invention and may be widely modified without departure from the invention and without going beyond the scope of protection of the claims.

Secured to the jaw or plate 12 inside of the spaces surrounded by the posts 17 and 18 are ratchet bars 21 and 22, each of which forms one element of a lock, the complementary element of which is constituted by a latch 23 in the post 17 and a latch 24 in the post 18. Each rachet bar is preferably formed from a strip of sheet or plate metal having teeth cut in its opposite edges and folded or bent about its longitudinal median 105 line to bring the teeth parallel to one another. Tongues or tabs 25 are formed on one end of the rachet bar and passed through slots in the plate 12 and bent outward in the same manner as the tongues 19 and 20. The latches 23 and 24 are alike and each consists of a bar having a toe 26 on one end, an

operating finger 27 extending at an angle from the opposite end, and lugs 28, 29 forming pintles extending laterally at opposite sides from points near the angle between the 5 body of the latch and the finger. The plate 11 is cut away over each of the posts 17 and 18 to provide a slot 30 with lateral notches 31, 32 of such dimensions and arrangement as to receive the finger 27 and pintles 28 and 10 29 freely. One of these slots is shown in Fig. 3, the other being covered by the operating bar presently described. The latch may be passed through the slot 30 into the interior of the post beneath, and its pintle lugs then 15 lie in the notches 31 and 32 and rest on the upper edge of the post. The finger 27 extends on an inclination through the slot 30 as shown in Figs. 2, 4, and 5.

An operating bar 33 extends longitudinally 20 of the plate 11 overlying the locations of the hollow posts. It is slotted and cut adjacent to each of these posts so as to provide a downwardly inclined tongue or abutment 34 and an upwardly inclined tongue or 25 abutment 35 with an open space between. The finger 27 of each latch passes through one of these open spaces. When the bar is placed in the normal position, which is that shown in Figs. 2 and 4, the 30 tongue 34 passes under the finger 27, raising the latter and bringing the latch toe 26 into engagement with one of the teeth of the ratchet bar, thereby locking the parts of the binder together so that they can not be accidentally separated. When in this position the control bar is locked against accidental 35 displacement by a shoulder 36 (Fig. 2) formed on a latch 37 which lies in a notch 38 in one end of the control bar, such shoulder 40 entering a recess 39 in the plate 11. A leaf spring 40 which is secured at one end to the bar overlies the latch and presses down upon the latter so that its shoulder 36 enters the recess 39 and is retained therein, but the 45 spring is yieldable to permit withdrawal of such shoulder from the recess by lifting up on a finger piece 41 of the latch. Said latch 37 is also preferably made as a stamping from stiff sheet metal and the finger piece is 50 formed by bending down one end. Adjacent to the opposite end of the latch piece are lateral lugs 42 which occupy notches extending from the slot 38, being retained in such notches by the pressure of spring 40, whereby force applied outwardly upon the finger piece is effective to slide the control bar end- 55 wise.

When the control bar is thus moved end- 60 wise to the left, with respect to the arrangement shown in the drawings, each down turned tongue 34 is withdrawn from engagement with the adjacent latch finger, and thereafter the upwardly inclined tongue 35 is caused to overlie and press down upon the 65 latch finger, swinging the latch so as to dis-

engage its toe from the ratchet bar, the complementary member of the lock. The parts of the binder are then unlocked and are free to be separated by lifting the upper plate or jaw from the lower one, thereby uncovering 70 the pile of leaves and withdrawing the inner members of the tubular posts from the outer members of such posts.

Preferably that portion of the plate 11 over which the control bar lies is depressed 75 to form a trough or channel in which the control bar lies and by the sides of which it is guided. Tongues 43 cut from the stock of the plate 11 are bent over the edges of such channel or guideway to retain the control bar therein. The depth of this channel is slightly greater than the combined thickness of the control bar and the retaining tongues 23, whereby the latter may be disposed substantially flush with the outer surface of those parts of the plate 11 at each side of the channel in order that the usual veneer of cardboard, leather, or other material which is placed over the outer surface of the plate may make extended smooth 90 contact therewith. The spurs 44, 45 are struck up from the plates 11 and 12, respectively to pierce the veneering layer and prevent the latter from becoming displaced.

In binders of small sizes there will be 95 ordinarily two of the telescopic posts with their associated locks. For large binders there may be three or more such posts. An important advantage of the improvement here described is that the manipulation of a 100 single control member or bar automatically causes the simultaneous and similar operation of all of the locks whether these be two, three, or more in number, making it unnecessary to manipulate each lock separately. 105 A further advantage is that the control bar will remain in the lock-releasing position until returned, and as long as it remains in this position the locks remain unlocked. When returned to the locking or normal 110 position the control bar is held by its latch shoulder 36 against accidental displacement. When it is in this position the finger piece 41 lies close to the leaves and is under the overhang of the plates and covers of the 115 binder, whereby it is guarded and is not liable to be accidentally caught and displaced. The construction here described adapts the binder to be made at minimum cost and at the same time to be extremely durable, since 120 all of the parts may be made by punch and die work from material such as sheet steel of a thickness of from one-fiftieth to one thirty-second of an inch more or less. As intimated before, however, so far as the 125 principles of the invention are concerned, other materials and other modes of making and assembling of parts may be employed within the scope of the invention as here claimed.

What I claim and desire to secure by Letters Patent is:

1. A loose leaf binder comprising opposed plates or jaws, complementary post elements on said plates, a toothed locking bar secured to one of the plates projecting toward the other, a coöperating latch engaged with the other plate in a manner permitting oscillative motion, having a toe to engage a tooth of said bar and having an inclined operating finger, and a controller movably mounted on the last named plate and formed with a slot in which said finger lies, having a tongue at one end of said slot projecting under said finger to place the latch in locking relation with the bar when the controller is moved in one direction, and having an element at the other end of said slot arranged to ride over and release the latch when the controller is moved in the opposite direction.
2. A loose leaf binder comprising opposed plates or jaws having leaf-engaging members, a plurality of toothed locking members carried by one of said plates, a plurality of complementary latches carried oscillatively by the other of said plates each arranged to interlock with one of said locking members, and each having an operating finger, and a single controller having tongues arranged to engage the fingers of all said latches and swing the latter into locking position when moved in one direction and having other portions arranged to engage the fingers of all the latches simultaneously to disengage the latches from the locking members when the controller is moved in the opposite direction.
3. A loose leaf binder comprising oppositely arranged plates, complementary telescopic tubular posts connected at one end to each of the respective plates and projecting toward the other plate, the posts of one plate being adapted to enter the posts of the other plate, toothed locking bars secured to one of the plates within the posts thereof, the other plate having slots over the adjacent ends of the posts which are secured to that plate, latches contained in the posts of the last-named plate, each having pintle portions to rest on the end of the post next to the plate, a toe to co-act with the adjacent locking bar, and a finger projecting through the slot in said plate, and a controller bar mounted movably on the last-named plate having slots through which the fingers of such latches pass, and provided with abutments on the opposite sides of said fingers for swinging the latches into engagement with the locking bars and out of engagement therewith as the controller bar is moved in one direction or the other.
4. A loose leaf binder comprising opposed plates or jaws, locking bars connected to one of said plates, coöperating latches pivotally engaged with the other plate for interlocking co-action with said bars, said latches having operating fingers, a controller bar movably mounted on the last-named plate having abutments arranged to engage the fingers of both latches on opposite sides as the controller is moved in one direction or the other for putting the latches into and out of engagement with the locking bars, and a finger piece connected with said controller having a shoulder adapted to interlock with a part of said plate for holding the controller in the position wherein it places the latches in such locking engagement.
5. In a loose leaf binder comprising opposed plates with leaf-engaging elements and complementary locking members and latches, an endwise movable controller bar for actuating said latches mounted on one of said plates, and a controller bar latch connected to said bar and having a shoulder, the plate having a recess to receive said shoulder when the controller bar is in normal position.

In testimony whereof I have affixed my signature.

WILLIAM H. AVERILL.
